WILLIAM F. GRANT, OF CLEVELAND HEIGHTS, OHIO, ASSIGNOR TO THE WILLMAN-SEAVER-MORGAN COMPANY, OF CLEVELAND, OHIO, A CORPORATION OF OHIO.

HYDRAULIC PUMP.

1,402,761.

Specification of Letters Patent. Patented Jan. 10, 1922.

Application filed July 24, 1919. Serial No. 312,962.

To all whom it may concern:

Be it known that I, WILLIAM F. GRANT, a citizen of the United States, residing at Cleveland Heights, in the county of Cuyahoga and State of Ohio, have invented a certain new and useful Improvement in Hydraulic Pumps, of which the following is a full, clear, and exact description.

This invention relates to a hydraulic pump.

The principal object is to provide a pump which is efficient and durable, which can be produced at relatively low cost, which is so designed as to the location of the pump and valves and number and arrangement of water passageways that in operation there is a minimum loss of pressure due to resistance and eddying, and so the pump block is silent in action, there being a total absence of noise due to the circulation of water, as exists when the latter is required to pass through tortuous passageways.

Further, the invention aims to provide a construction which minimizes the number of plugged passageways, thus providing greater safety than exists when the construction involves a number of passageways plugged at one end, with the constantly existing danger of the plugs being blown out if they are improperly seated in the threaded openings provided for them.

The invention may be briefly summarized as consisting in certain novel details of construction, and combinations and arrangements of parts which will be described in the specification and set forth in the appended claims.

In the accompanying sheet of drawings wherein I have shown a pump block composed of three pumps with three ports or valves associated therewith, Fig. 1 is a transverse sectional view of the pump block; Fig. 2 is a top plan view; and Fig. 3 is a vertical sectional view taken substantially along the line 3—3 of Fig. 2.

The hydraulic pump comprises a block 10 of metal which is preferably rectangular in contour, and may be of steel, or steel forging. The length of this block will depend upon the number of pumps and associated valves with which the unit is to be provided, the construction being such that there may be as many pumps and valves associat-

ed therewith as is desired from one to an indefinite number, three being shown in this instance.

The pumps comprise plungers 11, which can be operated in any suitable manner, as by rods power operated in any suitable fashion, these plungers extending down through combined guides and packing glands 12 into pump cylinders 13 which are drilled into the block 10, in this instance, vertically from the top side and near the rear face. The upper part of each pump cylinder 13 is made somewhat larger than the lower part to accommodate the packing and lower end of the packing gland and guide member 12.

Each pump has associated with it, two valves, which in accordance with the present invention are arranged in line with each other, and in this instance, one above the other, in the same valve chamber 14, formed by drilling into the block from the top and forwardly of the pump. In this valve chamber 14 is an exhaust valve 15, and below the latter an inlet valve 16, each valve consisting of a circular head which engages a tapered seat of the chamber, a guide extension which extends down from the seat, and an upper extension which extends up from the seat to limit the upward movement of the valve when it is unseated. The upper valve which is the exhaust valve, as before stated, is somewhat larger than the inlet valve, this construction being provided to enable the assembling and seating of both valves from the top of the valve chamber, which after the valves are in place, is closed by a plug 17.

The valve chamber 14 is drilled entirely through the block, and the lower portion just beneath the inlet valve 16 is threaded and receives an inlet or supply pipe 18, so that the water is admitted directly below and in line with the inlet valve.

From each valve chamber, at a point between the two valves of each pair, there extends a passageway 19, (shown in Figs. 1 and 3) to the lower part of the associated pump cylinder 13, this passageway serving both as an inlet and exhaust passageway, i. e. to deliver water to the pump cylinder, on the up stroke of the piston or plunger, and to convey it therefrom on the down stroke. This passageway 19 is formed by

drilling from the front face of the block through the valve chamber to the pump cylinder, the outer ends of each of these passageways 19 being closed by a threaded plug 20. It might be mentioned at this point that these plugs 20 are the only ones required to plug the ends of any of the water passageways so that in a pump block having one pump, there is required only one passageway closing plug, aside, of course, from the plug which closes the top of the valve chamber.

Extending horizontally through the block, and intersecting all the valve chambers 14, 15 is a delivery passageway 21 which intersects the valve chambers above the outlet valves 15. Screwed into both outer ends of this delivery passageway 21 are delivery pipes 22 and 23, which pipes when employed for 20 one purpose for which the pump block is very well adapted and used by me, i. e. to pump water from a tank to the hydraulic cylinder of a press, are provided respectively with a control valve and pressure relief valve. Additionally a delivery passageway 24 may be provided from the front of the block to one of the valve chambers, in this instance, to the middle valve chamber 14. Into the outer end of this passageway 30 may be screwed an auxiliary delivery pipe 25. The provision of this passageway 24 and delivery pipe 25 is not necessary, however, as the water may be delivered to the cylinder or other receiving element by suitable attachment to the delivery pipe 22 containing the control valve.

In operation, on the upstroke of the piston or plunger 11, or of the several plungers 11, the inlet valve 16 is elevated and 40 water flows from the supply pipe 18 (or pipes 18, as the case may be) into the passageway 19 and to the pump cylinder. On the down stroke of the piston or plunger the inlet valve is seated and the outlet valve 45 is unseated, water being forced by way of the passageway 19 and valve chamber up past the outlet valve 15 into the delivery passageway, and by way of the pipe 22 or pipe 25 to the cylinder or chamber to which 50 water is being pumped. When the inlet valve is unseated on the suction stroke, the extension on the upper part of the inlet valve engages the extension on the lower face of the exhaust valve to limit its movement. When the exhaust valve is unseated 55 on the power stroke of the pump piston or plunger, the extension at the top of the exhaust valve engages an extension on the bottom of the closure plug 17 which closes 60 the top of the valve chamber so as to limit the upward movement of the exhaust valve.

In using this pump block for supplying water under suitable pressure to the cylinder of a hydraulic press, when the control 65 valve is in one position and the pumps are

in operation, the water is pumped from the tank through the block, and back by way of the pipe 22 again to the tank, but when the control valve is in another position, the water is pumped from the tank 70 through the block and by way of the pipe 25 to the hydraulic cylinder, or in the event the pipe 25 is not utilized, by way of the pipe 22 and branch pipe leading therefrom which will be connected to the cylinder. 75

It will be seen, therefore, from the above description considered in connection with the drawings, that this pump has the desirable features mentioned at the beginning of the specification, the features of simplicity, ease of construction, durability and efficiency being particularly apparent. 80

Having described my invention, I claim:

1. A hydraulic pump comprising a one-piece block of substantially rectangular formation having pump cylinders formed therein, and valve chambers formed in the same, one for each pump cylinder, and arranged adjacent and substantially parallel thereto, each valve chamber containing an inlet valve and an exhaust valve in line with each other, and said block having a passageway extending from each pump cylinder to the associated valve chamber, and having supply and exhaust passageways communicating with the different valve chambers, the exhaust passageway extending from one end of the block through toward the opposite end thereof and intersecting the different valve chambers. 90

2. A one-piece block for a hydraulic pump of substantially rectangular contour having a plurality of pump cylinders formed in the same and extending from the top face downward, a plurality of valve chambers 105 extending from the top face to the bottom face, passageways extending from one side of the block and connecting each pump cylinder to one of the valve chambers, and a passageway extending endwise through the block and intersecting the valve chambers, said passageway having an outlet leading from at least one end of the block, and an outlet leading from the front face of the block. 110

3. A hydraulic pump comprising a one-piece block having pump cylinders formed in the same and valve chambers formed in the same, one for each pump cylinder and arranged adjacent thereto, each valve chamber containing an inlet valve and an exhaust valve in line with each other, and said block having a passageway extending from each pump cylinder to the associated valve chamber, and having supply and exhaust passageways communicating with the different valve chambers, there being an exhaust passageway extending from one end of the block to the other and having a delivery pipe connected to each end thereof. 120

4. A one-piece block for a hydraulic pump having a plurality of pump cylinders formed into the same and extending from the top face downward, a plurality of valve chambers extending from the top face to the bottom face, passageways extending from one side of the block and connecting each

pump cylinder to one of the valve chambers, and a passageway extending from one end of the block to the other and intersecting the valve chambers. 10

In testimony whereof, I hereunto affix my signature.

WILLIAM F. GRANT.

Certificate of Correction.

It is hereby certified that the assignee in Letters Patent No. 1,402,761, granted January 10, 1922, upon the application of William F. Grant, of Cleveland Heights, Ohio, for an improvement in "Hydraulic Pumps," was erroneously described and specified as "The Willman-Seaver-Morgan Company," whereas said assignee should have been described and specified as *The Willman-Seaver-Morgan Company*, as shown by the records of assignments in this office; and that the said Letters Patent should be read with this correction therein that the same may conform to the record of the case in the Patent Office.

Signed and sealed this 20th day of June, A. D., 1922.

[SEAL.]

KARL FENNING,
Acting Commissioner of Patents.
